UNITED STATES PATENT OFFICE

2,094,657

INDIRECTLY HEATED ELECTRONIC TUBE

Paul Kapteyn, Berlin, Germany

Application October 26, 1934, Serial No. 750,168
In Germany October 30, 1933

3 Claims. (Cl. 250—27.5)

The present invention relates to indirectly heated cathodes for electron discharge devices.

In the case of indirectly heated cathodes, and more particularly those having a bifilar filament, the free ends of the filament, and in certain cases the leads themselves, which for example in the case of so-called high-voltage cathodes are linked up, with an alternating potential amounting to approximately 50 volts cause a detrimental 10 secondary emission, particularly in case that the emissive surface is produced by means of the so-called metal vapour process. This secondary emission, which contributes appreciably to the total emission, results in humming noises, as its 15 potential reveals considerable fluctuations (for example of up to 40 volts) in relation to the anode during the duration of an A. C. period. The present invention has for its object a method of avoiding the stated interfering effects, and also 20 an electron discharge valve having an indirectly heated cathode, in which these effects are unable to occur.

The invention comprises an electron discharge tube including an indirectly heated cathode comprising an insulating tube, an equipotential tube surrounding the mid-portion of said insulating tube, said equipotential tube being provided with a highly emissive surface produced by means of the metal vapour process, the ends of said insulating tube projecting from said equipotential tube being at least partly coated with a black 25 good heat-radiating material, a heating spiral arranged within said insulating tube, the length of said heating spiral corresponding to the length 30 of said equipotential tube, and two connecting leads for said spiral, each of said leads projecting into one of the openings of said insulating tube, the diameter of each of said leads being so great 35 that no appreciable heating of said leads is produced by the heating current of said spiral.

The invention also comprises an electron discharge tube including an indirectly heated cathode comprising a rod consisting of insulating material, said rod being provided with two bores, two 40 heating filaments, each of said filaments being arranged in one of said bores, one connecting lead, each of the ends of said connecting lead projecting into one of the upper openings of said 45 bores and being connected to one end of each of said filaments, two further connecting leads, each of said further leads projecting into one of the lower openings of said bores and being connected to one of the other ends of said filaments, each 50 of said leads having a diameter which is at least five times as great as the diameter of each of said

filaments, a cap surrounding the upper part of said rod, an equipotential layer surrounding at least the mid-portion of said rod, and a highly emissive substance arranged on said equipotential layer. 5

Two embodiments of the invention are shown by way of example in the appended drawing.

In Fig. 1 there is shown an equipotential cathode, in which the leads are introduced at either end of the insulating tube and are connected 10 with the heating filament preferably by welding, while in

Fig. 2 there is shown a cathode having a double-wound filament wire in the arrangement according to the invention. 15

Fig. 3 shows how the heating spirals are secured at the connecting leads.

In the drawing 1 is the insulating tube, which may consist for example of any suitable ceramic material, such as porcelain, magnesia or the like, 20 2 the equipotential tube, 3 the highly emissive layer, and 5 the wound filament, which is secured to current leads 6 and, in accordance with the invention, may preferably possess the same length as the highly emissive layer. The leads possess 25 in accordance with the invention a considerably greater cross-section than the filament. Preferably the cross-section of the leads is so chosen that they fit exactly into the respective bores of the insulating tube. The leads are firmly connected 30 within the insulating tube with the ends of the filament. In this manner it is accomplished that the leads projecting from the cathode are kept cool, and outside of the insulating tube there are no metallic portions traversed by heating current which possess as high a temperature as is necessary for producing an appreciable emission. It is naturally also possible and desirable in accordance with the invention to provide suitable 35 additional means having good heat radiating properties for keeping the ends of the cathode cool. For example in the arrangement of Fig. 1 there may be provided at either end of the equipotential surface a coating of a black substance, such as platinum black or a colloidal dispersion 40 of graphite and/or carbon in a suitable solvent, (quadag).

In Fig. 2 there is illustrated by way of example an embodiment of an equipotential cathode with a bifilar filament. The reference characters are 50 the same as those employed in Fig. 1. In this arrangement the current leads, which possess a low temperature, may conveniently be employed at the same time for holding the equipotential cathode in the press portion 8 of the valve. The 55

ends 7 of the heating filament project from the insulating tube, and these projecting ends are firmly connected electrically over their entire length with the leads forming so to say a part of said leads which possess externally a cross-section of such nature that an increase in temperature up to the extent of self-emission is safely avoided.

As shown in Fig. 2, the ends of the filament 10 may for example not only form contact with the leads within the insulating tube but may also be connected with the electrodes outside the insulating tube, for example by spot-welding. At the reversing point in the upper part of the 15 cathode there is provided likewise for the purpose of accomplishing the desired effect a thick, curved lead, and the upper opening of the cathode is closed by suitable means, for example by an 20 adapted layer of porcelain or other ceramic substance. On the other hand, the equipotential tube 2 may be so constructed as to cover said opening.

The diameter of the feeding leads should be in each case considerably greater than the 25 diameter of the heating filament, say, at least five times as great as the same.

The essential advantage of the construction according to the invention consists in complete 30 elimination of the disturbances occurring in the case of indirectly heated high-voltage cathodes, and more particularly cathodes produced according to a metal vapour process, with a considerably 35 more simple method of production, which is simple to perform from the point of view of manufacture and is considerably cheaper as compared with the methods hitherto employed.

It is naturally also possible to make use in addition of the arrangements as are described in my 40 application Ser. No. 677,526 and to screen off in special fashion the leads to the heating wire and 45 the remaining electrodes against impinging metallic vapour resulting upon the activation of the cathode, or against each other in the case of any interfering electrons which may result.

The arrangement of the invention is suitable 50 not only for single-system tubes, but also more particularly for multi-stage tubes, as in the case of such tubes a simple, space-saving construction 55 is of peculiar importance, whereat said systems may comprise one or several plates and/or several grids which may be constructed and arranged in a manner known per se.

For accomplishing the desired effect not only 60 the diameter, but the material of the leads also 65 plays an important part. According to the invention the ratio of the resistances of the leads and of the filament per unit of length should be 70 preferably not less than 1:10. A narrowly wound spiral filament of tungsten wire of 50μ and leads

consisting for example of nickel of .4 mm. diameter would correspond to the above condition.

I claim:

1. An indirectly heated cathode comprising a rod consisting of insulating material, said rod being provided with two bores, two heating filaments, each of said filaments being arranged in one of said bores, one connecting lead, each of the ends of said connecting lead projecting into one of the upper openings of said bores and being 10 connected to one end of each of said filaments, two further connecting leads, each of said further leads projecting into one of the lower openings of said bores and being connected to one of the other 15 ends of said filaments, each of said leads having a diameter which is at least five times as great as the diameter of each of said filaments, a cap surrounding the upper part of said rod, an equipotential layer surrounding at least the mid-portion of said rod, and a highly emissive substance arranged on said equipotential layer. 20

2. An indirectly heated cathode comprising a rod consisting of insulating material, said rod being provided with two bores, two heating filaments, each of said filaments being arranged in one of said bores, one connecting lead, each of the ends of said connecting lead projecting into one of the upper openings of said bore and being connected to one end of each of said filaments, two further connecting leads, each of said further leads projecting into one of the lower openings of said bores and being connected to one of the other ends of said filaments, each of said leads having a diameter which is at least five times as great as the diameter of each of said filaments, a cap surrounding the upper part of said rod, an equipotential layer surrounding at least the mid-portion of said rod, and a highly emissive substance arranged on said equipotential layer, and two coatings of good heat-radiating material, 30 each of said coatings being arranged at one end of said insulating tube. 35

3. An indirectly heated cathode containing a rod of insulating material, said rod provided with two borings, two heating filaments arranged in 45 said borings, the diameter of said borings being at least five times as great as the diameter of said filaments, said filaments connected on the upper ends with a lead and connected on both lower ends with two leads, said leads having the same 50 diameter as said borings and projecting into said borings to approximately a fourth part of the whole length of said borings for preventing emission of said heating filaments out of said borings, an equipotential layer surrounding at least the 55 mid-portion of said insulating rod coated with an emissive substance, a cap surrounding the upper part of said rod. 60
